UNITED STATES PATENT OFFICE.

CALLIE MARILIS GRAHAM, OF PARKER, ARIZONA.

REFRIGERATOR.

1,219,936.

Specification of Letters Patent. Patented Mar. 20, 1917.

Application filed February 17, 1916. Serial No. 73,879.

To all whom it may concern:

Be it known that I, CALLIE M. GRAHAM, a citizen of the United States, and a resident of Parker, in the county of Yuma and State of Arizona, have invented a new and useful Improvement in Refrigerators, of which the following is a specification.

My invention is an improvement in refrigerators, and the invention has for its object 10 to provide a refrigerator of the character specified, wherein an ice receiving chamber and a series of food receiving chambers are provided, so arranged that the air will circulate down through the ice chamber to be 15 cooled and will pass around the food receiving chambers to absorb the heat from the material to be refrigerated and will again pass upward to be again cooled, thus providing a continuous circulation through 20 the refrigerator and about the ice and the material to be refrigerated.

In the drawings:

Figure 1 is a perspective view of the improved refrigerator,

25 Fig. 2 is a vertical section,

Figs. 3 and 4 are sections on the lines 3-3 and 4-4, respectively, of Fig. 2, each looking in the direction of the arrows adjacent to the line,

30 Fig. 5 is an enlarged sectional detail of the drain trap, and

Fig. 6 is a perspective view of the upper end of the pipe and the cap for the same.

In the present embodiment of the invention an outer casing 1 of wood is provided, the said casing being divided into an ice compartment and into three storage compartments by vertical partitions 2 and transverse partitions 3 and 4. The casing is also 40 provided with feet 5 for supporting the same but of contact with the floor, and the feet are preferably provided with casters or rollers 6, as shown.

The compartments open at the front of 45 the casing and doors 7, 8, 9 and 10 are provided for closing the several compartments, the doors being hinged to the casing and having latches for holding them in adjusted position.

50 A lining 11 of paper is arranged within the wooden casing 1, and a lining 12 of asbestos is arranged within the lining 11. A second lining 13 of paper is arranged on the inner side of the asbestos lining, and a 55 heavy layer 14 of cork is arranged between the lining 13, and a lining 15 of paper,

which holds the cork in place. The linings 11, 13 and 15 are all preferably made of water-proof paper to prevent moisture reaching the asbestos lining 12.

60 A thin lining 16 of wood is arranged on the inner side of the lining 15 of paper, and the wall is completed by a lining 17 of galvanized tin. The doors 7, 8, 9 and 10 are formed of layers in precisely the same manner as the wall, and the door openings and the door edges are faced with wood as shown at 19 in Figs. 3 and 4.

65 The several compartments are formed by minor casings which fit within the major or main casing; and these minor casings are supported by substantially U-shaped cross bars 20, which are arranged with their bodies upward and their side walls depending, and the bars are held in place in any 70 suitable manner, such as by soldering.

75 A casing 22 is arranged within the compartment closed by the door 8; and a similar casing 23 is arranged within the compartment closed by the door 9. A smaller and 80 similar casing 24 is arranged within the compartment closed by the door 10, and a casing 25 having its lower and upper ends closed by sheets or screens 26 of perforate material is arranged within the compartment 85 at the door.

A drip pan 27 rests on the cross bars 20 at the compartment adjacent to the door 7, and a number of U-shaped brackets 28 are arranged in the pan, the said brackets being 90 arranged across the ice chamber and having their bodies resting in the bottom of the pan and having their side walls extending upward and riveted to a corrugated sheet 29 of metal upon which the ice indicated at 30 is adapted to rest. This casing 25 has its lower end seated in the pan 27, and the sheet 29 of corrugated material is of a size such that the side walls of the casing 25 will not engage the sheet.

100 The minor casings 22, 23 and 24 are provided with transverse shelves or partitions 31 of perforate material as shown in Figs. 2 and 4. These partitions or shelves are supported by brackets 32 on the walls of the casing. It will be noted from an inspection of Fig. 2 that the casings 22 and 23 have openings or perforations 34 in their tops in order to permit a free circulation of air and which are covered by wire mesh 34.

110 The drip pan 27 has a depression 35 in one corner and a drip pipe 36 has its upper end

extended through an opening into the depression. It will be noted from an inspection of Fig. 5 that the upper end of the pipe extends above the bottom of the depression 5 and a cap 38 is seated in the depression over the upper end of the pipe. This cap has recesses or notches 39 in its lower edge which permit the drip or melted ice to flow into the pipe but prevent the entrance of air through 10 the pipe and the pipe extends through the bottom of the casing 1 as shown in Fig. 3.

The melted ice passes down from the corrugated sheet 29 into the drip pan and finally reaches the depression 35. It will be 15 noticed that the upper end of the pipe 36 is a trifle higher than the tops of the notches 39, so that air cannot enter the ice compartment through the drip pipe.

The circulation of air is indicated in Fig. 20 2 by the arrows, and it will be noticed that the air passes down through the sheet 26 at the top of the casing 25 around the ice and down between the side edges of the corrugated sheet and the drip pan. The air 25 passes over the sides of the drip pan and down around the minor casings 24 and 23, and then passes upward around the casing 22. The interior of the casing is thus thoroughly aerated and refrigerated. The 30 material to be refrigerated, as for instance, food of suitable character is supported by the perforate shelves 31, and the cooled air has access to every part of the said material.

For family use the ice chamber, that is, 35 the space within the casing 25 will have a capacity of one hundred and thirty-five (135) pounds of ice and the ice will be supported out of contact with the walls of the chamber. It will be noticed from an inspection of Figs. 3 and 4 that the door 7 closes the front of the ice chamber, that is, the compartment 25, while the doors 8, 9 and 10 close the open fronts of the casings 22, 23 and 24.

45 Each food chamber, as also the ice chamber,

has on each side an air space and in practice this space will be at least two inches in thickness. That is, there will be a space of at least two inches between the wall of each casing 22 to 25 and the galvanized lining of the casing 1. The cold air passing downward forces the heated air upward which then comes in contact with the ice and is in turn cooled to pass downward to drive upward the cooled air which has absorbed heat from the articles to be refrigerated and the circulation is continuous.

Each opening into the ice chamber is carefully screened to prevent any foreign substance from entering. Each food chamber 60 is encircled by a layer of cold air, and the larger chambers 22 and 23 have the openings at their top to permit a circulation from the interior thereof. The chamber 24 is especially designed for receiving butter, eggs 65 and milk.

It will be noticed that facing strips are arranged between the casings and connected to the edges thereof, the facing strips forming the partitions 2, 3 and 4.

70 I claim:—

A refrigerator comprising a casing having a non-heat conducting lining and provided with minor metallic casings for receiving the material to be refrigerated and 75 the ice to refrigerate, said minor casings being supported loosely in the main casing and being spaced apart from the walls thereof and from each other to permit the free circulation of air about and between said minor 80 casings, a drip pan in connection with the casing for the ice, each of said material receiving casings having shelves of perforate material, and the ice-receiving casing having ends of perforate material and supported by the drip pan.

85 CALLIE MARILIS GRAHAM.
